(57) **CLAIM**

The ornamental design for a couch cover, as shown and described.

DESCRIPTION

FIG. 1 is a front, left, top perspective view of a couch cover showing my new design;

FIG. 2 is a back, right, bottom perspective view thereof;

FIG. 3 is a front view thereof;

FIG. 4 is a back view thereof;

FIG. 5 is a right view thereof;

FIG. 6 is a left view thereof;

FIG. 7 is a top view thereof;

FIG. 8 is a bottom view thereof; and,

FIG. 9 is an enlarged perspective view thereof, taken from selected portion 9 in FIG. 1.

The dash dot broken lines in the drawings depict enlarged view indicators and form no part of the claimed design.
